(57) **CLAIM**

The ornamental design for a hinge for furniture, as shown and described.

DESCRIPTION

FIG. 1 is a perspective view of the front, left and top of a hinge for furniture showing my new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof;

FIG. 8 is a top plan view in an alternate open position thereof;

FIG. 9 is a top plan view in a second alternate open position thereof;

FIG. 10 is a perspective view shown in use thereof;

FIG. 11 is another perspective view shown in use thereof; and,

FIG. 12 is another perspective view shown in use.

The elements shown in broken lines are for illustrative purposes only and form no part of the claimed design.
